ATTORNEY

UNITED STATES PATENT OFFICE.

CHARLES C. FIELDS, OF BALTIMORE, MARYLAND.

LETTER-CARRIER'S TABLE.

SPECIFICATION forming part of Letters Patent No. 653,004, dated July 3, 1900.

Application filed April 24, 1900. Serial No. 14,100. (No model.)

To all whom it may concern:

Be it known that I, CHARLES C. FIELDS, a citizen of the United States, residing at Baltimore, in the State of Maryland, have invented 5 certain new and useful Improvements in Letter-Carriers' Tables, of which the following is a specification.

My invention is an improvement in "routing-tables" for letter-carriers' use, and has 10 for its object to provide a table of this character which will assist and expedite a letter-carrier's work and which will be of cheap and simple construction.

Preparatory to going out upon his route a 15 carrier is obliged to arrange his papers and letters according to streets and the numbers of houses on the streets, which is called "routing," and considerable difficulty has heretofore been occasioned in providing suitable 20 means for assisting the carrier to arrange his mail in the orderly manner necessary.

The invention consists in the construction, arrangement, and combination of the parts hereinafter fully described and claimed, reference 25 being had to the accompanying drawings, forming part of this specification, in which—

Figure 1 is a front elevation of my improved routing-table with a part broken away. Fig. 30 2 is a vertical transverse section of the table on the line $x-x$ of Fig. 1, illustrating the means for automatically keeping the paper-supporting slide extended. Fig. 3 is a plan view of the table-top, illustrating the paper 35 and letter supporting slides; and Fig. 4 is a perspective view of a portion of the table-top, showing the letter-supporting slides.

Referring to the drawings, A designates the top of the table, which is provided near 40 one side with a guideway a , whose side walls are undercut, as shown in Fig. 1, and which opens at its rear end into a well a' , extending below the top. A newspaper-supporting extensible slide B fits accurately in the guideway 45 a , with its upper surface flush with the upper surface of the top A, and the rear portion of the said slide is composed of slats b on a flexible strip b' and is adapted to slide in the well a' , being drawn down into the well. 50 by a contractile spring a^2 , which is secured to the lowermost slat and the bottom of the well. The slide B is also provided with a stop-plate

b^2 at its front end to prevent the papers falling off the slide at such point.

C designates a longitudinally-extending series of beveled notches on the under side of the slide B, in any one of which a spring-pressed catch in the form of a sliding bolt D, on the front of the table below the top, is adapted to fit to hold the slide when extended 60 to different points against the action of the spring a^2 . The bolt D has a beveled end d , which slides over the beveled walls of the notches C as the slide is extended.

E is a hook on the back of the table; a short 65 distance above the slide B, on which the letter-carrier may hook his strap and lay the same along on the slide B. Now when the letter-carrier is ready to "route" his mail, it being understood that the slide B is at the 70 inner limit of its movement, he hooks his strap on the hook E and lays the strap along the slide. He then takes the newspapers and lays them in proper order over the strap on the slide, and as the number of papers increases he draws out the slide farther and 75 farther, the bolt D sliding over the notches C and automatically holding the slide extended. When the carrier's quota of newspapers for his trip is completed, he unhooks the end of 80 his strap and binds them into a bundle. The bolt D is then withdrawn, and the spring a^2 draws the slide back into inner position.

In the table-top A, at one side of and at a suitable distance from the paper-supporting 85 slide B, two guideways f are formed, having their outer walls undercut and being separated by a guiding-strip F. In these guideways are fitted two letter-supporting slides G, each slide being formed with a longitudinally-recessed side edge g , which lies over the guiding-strip F and abuts against the corresponding side edge of the other strip.

H designates a stop-plate secured to one end of each slide G and adapted to hold the 95 letters upright on their edges as they are being arranged.

Supported above the table-top A is a rectangular frame K, whose vertical members are formed with horizontal grooves, and L 100 designates a filing-case divided into a number of pigeonholes and having side strips I fitted to slide in said grooves, so that the case may be drawn outward toward the letter-car-

rier in order that he may conveniently file mail therein and then push the case back into the frame K.

I' designates a stop on the bottom of the case adapted to abut against a similar stop I² on the frame to limit the outward movement of the case L.

It will be seen that I have provided a very complete device for letter-carriers' uses, which is simple in construction and which will greatly aid the carrier in routing and filing his mail.

Having thus described my invention, what I claim as new, and desire to secure by Letters Patent, is—

1. A device of the character described, comprising a table having a top formed with a guideway and a well into which the guideway opens, a paper-supporting slide fitted in said guideway flush with the upper surface of the table-top and having a flexible rear portion arranged in the well, the lower face of said slide being formed with notches, a spring secured to the flexible portion of said slide and adapted to draw the same into the well, and a spring-pressed catch on the front of the table below the top and adapted to take into the notches to hold the slide at various extensions.

2. In a device of the character described, a

table having a top formed with a guideway and a well extending below the top into which the rear of the guideway opens, a paper-supporting slide fitted in said guideway flush with the upper surface of the table-top and having a slatted rear portion movable in the well, said slide being also formed with a series of notches extending from the slatted portion to the front end of the slide, a stop-plate at the front end of the slide, a contractile spring secured to the lowermost slat and the bottom of the well and adapted to draw the slide inward, and a spring-pressed sliding bolt on the front of the table below the top and adapted to take into the notches to hold the slide at various extensions.

3. A letter-carrier's table formed with two guideways f and a guiding-strip F separating said guideways, and two letter-supporting slides fitted in said guideways and each of which is formed with a recessed side edge lying over the strip and abutting against the corresponding edge of the other slide, and a stop-plate secured to one end of each slide.

In testimony whereof I affix my signature in the presence of two witnesses.

CHARLES C. FIELDS.
